(57) **CLAIM**

The ornamental design for an outdoor lantern with hand-painted shade, as shown and described.

DESCRIPTION

FIG. 1 is a perspective view of my outdoor lantern with hand-painted shade, showing my new design;

FIG. 2 is a front elevational view;

FIG. 3 is a rear elevational view;

FIG. 4 is a right side elevational view wherein the left side elevational view is a mirror image thereof;

FIG. 5 is a top plan view; and,

FIG. 6 is a bottom view.
